FIG. 3.

INVENTOR
CORNELL FLAGSTAD
BY ATTORNEY

UNITED STATES PATENT OFFICE.

CORNELL FLAGSTAD, OF MINNEAPOLIS, MINNESOTA, ASSIGNOR OF NINETY-FIVE PER CENT TO THE FOLDING CRATE AND BOX CO., A CORPORATION OF MINNESOTA, AND FIVE PER CENT TO OSCAR A. FLAGSTAD, OF MINNEAPOLIS, MINNESOTA.

CRATE.

Original application filed November 26, 1923, Serial No. 677,175. Divided and this application filed May 9, 1927. Serial No. 189,807.

This invention relates to crate constructions and the primary object is to provide a novel construction of crate and a cover therefor, in which the cover may be easily and quickly secured and released with respect to the crate, the latter of which may be either of the collapsible or stationary type although the collapsible or folding crate provides the greatest field for the adaptation and use of the specific 10 cover and cover locking means hereinafter set forth. Further and more specific objects will be disclosed in the course of the following specification, reference being had to the accompanying drawing, wherein:

15 Fig. 1 is a top or plan view of a collapsible crate embodying my improved cover and cover locking device.

Fig. 2 is an enlarged detail section on the line 2—2 in Fig. 1.

20 Fig. 3 is a sectional detail view, similar to Fig. 2, but showing the adjacent cover and crate sections as sprung from their normal positions to effect the locking and unlocking operations.

25 Fig. 4 is an enlarged detail section, on the line 4—4 in Fig. 1.

Figures 1, 2, 3, and 4 are similar to Figures 15, 17 and 16, respectively, of my co-pending application, Ser. No. 677,175, filed November 30 26, 1923, for collapsible crate, of which the present application is a division.

Referring to the present drawings more particularly and by reference characters, A, B, C, and D designate the vertical sections of 35 the crate, all of which are connected, at their adjacent ends, by hinges E. In the present instance sections A and B, being the shorter, may be termed the end sections, and sections C and D as the side sections, but it will be 40 understood that with the proportionate lengths reversed, then sections A and B may be considered as side sections and sections C and D as end sections. The hinges E may be of any suitable type which will permit the sections A, B, C and D to be collapsed against

each other when the cover and base sections of the crate have first been released. No base section is shown, but it is understood that it may be similar to the cover section shown, and which is designated, generally, by the letter F.

The cover section consists, primarily, of two interslably arranged and interlocked frames 5 and 6, the first of which is made up of longitudinal slats 7, 8 and 9, and transverse slats 10, and the latter of which is made up of longitudinal slats 11 and 12, and transverse slats 13. The vertical sections A—D, inclusive, are preferably made up of vertical slats 14, connected as by horizontal slats or bars 15.

The cover frames have a limited sliding movement with respect to each other, which is utilized in securing and detaching the cover. The longitudinal bars 11 and 12, of the respective frames 6 and 5, project beyond the ends of the cover so as to rest on the end sections A and B, near their outer ends, and thus retain the cover in place. The frame 5 is provided, near two corners of the cover, with a pair of rigid fingers 16, which are long enough to engage into or under the rail 15 of the side section C, and are preferably first set into place when the cover is to be secured, at which time the frames are collapsed as far as possible. Near the opposite corners of the crate, 75 the frame 6 is provided with a pair of rigidly secured end fingers 17, arranged to engage in or under a pair of strap members 18 secured to the inner sides of the side section D. These fingers are moved into position by pulling out the cover frame 6 from the frame 5. When the frames have been pulled apart the required distance, a spring latch 19 carried by one of the transverse slats 13, of the frame 6, snaps against the center slat 8 of the frame 5, and thus holds it locked until the latch is manually released.

At this time the ends of the slats 11 and 12 rest upon the end sections, the fingers 16 and 17 engage the side sections, and the cover

is locked in a comparatively rigid condition substantially as a single piece or unit. For further locking the cover, however, and for the purpose of preventing bulging of the various sections, with respect to each other, I have provided the ends of the cover with a pair of rigid hooks 20, and the sides of the cover with rigid hooks 21, all of which engage and co-operate with suitable means, such as straps 22, of the vertical sections. The hooks 20 and 21 are far enough removed from the bearing points 16, 17, 11^A, 11^B, 9^A, and 9^B, of the cover upon the crate, to permit the intermediate portions of the cover to be sprung from their normal positions of rest and, as the hooks are not slideable or movable with respect to the cover, it will be seen that they may only be engaged by simultaneously and also springing the vertical sections of the crate out with respect to the sprung portions of the cover. This double springing is clearly illustrated in Fig. 3, and while it is very simply and easily effected it will be seen that the resulting connection is a very strong one and cannot be loosened or released by internal pressure but must have the combined internal and external springing actions, which can only be done by proper manual manipulation. It will also be noted that while the locking of the hooks 20-21 has been described and is possibly best effected after the cover frames have been locked into a single unit, the hooks 21 (but not 20) may be moved outwardly with the cover frames, thus not necessarily requiring the side section, as D, to be sprung out. With the hooks 20, it is of course always necessary to effect both springing motions.

It is understood that suitable modifications may be made in the general design and structural details of the invention as herein shown, provided, however, that said modifications come within the spirit and scope of the appended claims.

Having now therefore fully shown and described my invention, what I claim to be new and desire to protect by Letters Patent is:

1. The combination with a crate, of a cover therefor adapted to be sprung in respect to its normal position of rest on the box and having fasteners rigidly secured thereto for interlocking engagement with side sections of the crate, said fasteners being arranged to be held in interlocking engagement by the spring tension of the cover.

2. A crate having a cover section and a vertical section both of which are adapted to be sprung, with respect to their normal positions of rest, a fastener rigidly carried by one of said sections for interlocking engagement with the other section when both of the sections are sprung with respect to said normal positions, said fastener being arranged so as to be held in interlocked position by the spring tension of one of the sections.

3. A crate having a cover and a vertical

section both of which are adapted to be sprung with respect to their normal positions, a fastener carried by and rigidly secured to the cover for interlocking engagement with the vertical section when both are sprung, said fastener being arranged so as to be held in interlocked position by the spring tension of the cover.

4. A crate having a cover and a vertical section both of which are adapted to be sprung with respect to their normal positions, a fastener carried by and rigidly secured to the cover for interlocking engagement with the vertical section when both are sprung, said fastener being arranged so as to be held in interlocked position by the spring tension of both the cover and the vertical section.

5. A crate having two sections separable with respect to each other and one of which is adapted to be sprung inward and the other outward with respect to their normal positions, a fastener carried by one of the sections for interlocking engagement with the other section, when both of the sections are so sprung.

6. A crate having two sections separable with respect to each other and one of which is adapted to be sprung inward and the other outward with respect to their normal positions, a fastener carried by one of the sections for interlocking engagement with the other section, when both of the sections are so sprung, said fastener being arranged so as to be held in interlocking engagement by the spring tension of one of the sections.

7. A crate having two sections separable with respect to each other and one of which is adapted to be sprung inward and the other outward with respect to their normal positions, a fastener carried by one of the sections for interlocking engagement with the other section, when both of the sections are so sprung, said fastener being arranged so as to be held in interlocking engagement by the spring tension of both of the sections.

8. A crate having two sections separable with respect to each other and one of which is adapted to be sprung inward and the other outward with respect to their normal positions, a fastener carried by one of the sections for interlocking engagement with the other section, when both of the sections are so sprung, said fastener consisting of a hook member rigidly secured to the section by which it is carried and adapted to be received by the other section.

9. The combination with a crate having vertical side and end sections, a cover for closing the crate and adapted to have its ends carried upon the upper ends of the end sections, said cover being adapted to be sprung downward, intermediate its ends, between the side sections, said side sections being adapted to be sprung outward, intermediate their ends, from the cover, and fasteners carried

by the sides of the cover for engagement with the side sections by so springing the cover and side sections, to thereby firmly fasten the sides of the cover to the side sections.

5 10. A crate having two sections separable with respect to each other and one of which is adapted to be sprung inward and the other outward with respect to their normal positions, a fastener carried by one of the sections

for interlocking engagement with the other 10 section, when both of the sections are so sprung, one of said sections forming a cover for the crate and comprising two interslidiably connected frames having a limited sliding movement with respect to each other. 15

In testimony whereof I affix my signature.

CORNELL FLAGSTAD.

CERTIFICATE OF CORRECTION.

Patent No. 1,690,896.

Granted November 6, 1928, to

CORNELL FLAGSTAD.

It is hereby certified that the above numbered patent was erroneously issued ninety-five percent to "The Folding Crate and Box Co., a corporation of Minnesota, and five percent to Oscar A. Flagstad, of Minneapolis, Minn.", whereas said patent should have been issued to the inventor said "Flagstad, ninety-five percent to The Folding Crate and Box Co., a corporation of Minnesota, and two and one-half percent to Oscar A. Flagstad, of Minneapolis, Minn., as shown by the records of assignments in this office; and that the said Letters Patent should be read with this correction therein that the same may conform to the record of the case in the Patent Office.

Signed and sealed this 11th day of December, A. D. 1928.

(Seal)

**M. J. Moore,
Acting Commissioner of Patents.**
